AUTOMATIC MUSICAL INSTRUMENT

Gordon Butler Illes, Broadstairs, England

Application November 25, 1932, Serial No. 644,313
In Great Britain December 16, 1932

11 Claims. (Cl. 84—43)

This invention relates to automatic musical instruments such as pneumatic piano players and the like and to improved apparatus for enabling some note or notes to play at one pressure, while another note or notes play simultaneously at another pressure, no matter where the group of notes is located in the compass of the piano.

The invention contemplates a novel form of method and apparatus which is noted for its 10 simplicity and compactness.

According to the present invention there is provided in for example a pneumatic piano player adapted to strike notes with different degrees of force, control apparatus so connected with co-operating note holes in the tracker bar that the changing over or altering of the exhaust tension applied to the pneumatic of a note hole is effected by the uncovering of another note hole which for this purpose functions as a control for the 20 playing power of the first mentioned note hole.

Thus according to the present invention there is provided in a pneumatic piano player adapted to strike notes with different degrees of force control apparatus so connected with co-operating note holes in a tracker bar that a note hole when exposed by a perforation in the music roll is capable of playing its own note, cancelling the playing power of another note hole, and changing over the degree of exhaust which may be applied 30 to a note of a further note hole.

With apparatus according to the present invention, an addition of one valve for each note is made. By reason of their function these valves will hereinafter be called selector valves.

The selector valves may themselves be similar 35 to the striking pneumatic valves used in the ordinary piano player. Their object is to determine whether the striking pneumatic shall be actuated by the soft wind or heavy wind, or to alter the 40 exhaust tension.

Each selector valve in certain constructions hereinafter described, places the ordinary valve of the player-piano which it controls in communication with either of two wind ways, according as to whether it is in its normal position, or has been moved by its purse. These wind ways are charged with two distinct degrees of exhaust, and both may be variable.

In another arrangement a common wind way 50 is used whereby each note is given its own separate expression value, that is to say, the playing force of the note is controlled.

The accompanying drawings illustrate by way 55 of example certain ways of carrying out the

present invention. All the views are in dia-grammatic form.

In the drawings:—

Fig. 1 is a sectional view showing the tracker bar and control apparatus in the action rail or beam.

Fig. 2 a plan view of a music roll travelling downwards.

Figs. 3 and 4 views of selector valves and vacuum ducts.

Fig. 5 is a sectional view showing the tracker bar and a further form of control apparatus.

Fig. 6 is a plan view of the action rail or beam shown in Fig. 5.

Fig. 7 is a sectional elevation of an entire as-sembly using a common wind-way hereinafter referred to.

Fig. 8 shows a sectional view of another form of selector valve.

Figs. 9 and 10 are additional valves herein-after referred to.

Figs. 11 and 12 are diagrammatic views of electro-pneumatic control apparatus.

Fig. 13 is a view of a selecting valve which may be used in the construction of Fig. 7.

Referring to Fig. 1, *a* is the tracker bar having note-holes *b*. *c* is an action rail or beam, and *d*, *d*¹, and *e* are chambers provided in the action beam. *f* and *g* are rigid tubes passing centrally through the chambers *d* and *d*¹ to the chamber *e*, each chamber *e* being common to a pair of cham-bers *d* and *d*¹ through the tubes *f* and *g* when the membranes *h* and *h*¹ are drawn away from the tubes *f* and *g* by reason of a degree of ex-haust in the chambers *i* and *j* which correspond with the chambers *d* and *d*¹. The chambers *j* are all rendered common by means of a grooved rail *k*. The chambers *i* and *e* are sealed with pneumatic cloth *l*. It is to be understood that each note hole has separate chambers *d*, *d*¹, *e*, *i* and *j* allotted thereto.

Each tube *m* leading from a note-hole *b* has branches *m*¹ and *m*², the branch *m*¹ leading to the chambers *d* and *d*¹. From the chamber *d*¹ there is a tube *n*.

The tube *m*² is connected to the chamber *i* allotted to the chamber *d* of the note-hole next on the left looking from the front (that is to say the bass side) and so on down the key-board from top to bottom.

The tube *o* communicates with the purse cham-ber *p* (see Fig. 7) of the striking pneumatic valve *t* of the note played by the particular note hole *b* shown, whereas the tube *n* communicates with the purse chamber *q* of the selecting valve *s* not

corresponding to the striking pneumatic valve above mentioned, but to the selecting valve governing the ordinary or striking pneumatic valve next on the right (or in other words the next note on the treble side) and so on up the keyboard from bottom to top.

Fig. 2 shows a plan of part of a music roll *r* showing the accented and unaccented notes. The notes 1 are unaccented and the notes 2 and 2^a are accented and require accenting holes or perforations 3 and 3^a.

As stated the notes 2 and 2^a are accented notes, and the function of the selecting valves in certain constructional forms is to change over from light wind (lower exhaust) to heavy wind (higher exhaust).

To follow the operation of the apparatus assume two adjacent note holes *b* in the tracker bar.

Now assuming it is required that the perforation 3 must not play a note in order to prevent a dissonance. This is effected by the apparatus in Fig. 1 in the following way.

Let it be assumed that by reason of suitable bleeds or vents all the tubes *m* are normally subject to exhaust, and the chambers *j* are normally at atmospheric pressure.

The perforation 2^a when it uncovers its co-operating hole *b* in the tracker bar *a* will send a pulse along the tube *m*. This pulse will be divided and pass along *m*¹ through the chambers *d* and *d*¹ to the tube *n* and thence to the purse chamber *q* of the selector valve *s* corresponding to the note that is played from a hole in the tracker bar on the right hand side of the perforation 2^a (Fig. 2). There is however no perforation in the paper corresponding to this note hole in the tracker bar and consequently the action is abortive. The chambers *d* and *d*¹ are now charged with outer air.

The pulse passing through the tube *m*² will fill the chamber *i* corresponding to the note hole uncovered by the perforation 3^a with outer air. This will cause the membrane *h* also corresponding to the perforation 3^a to be inflated, thus sealing the corresponding tube *f* and preventing any communication between the note hole uncovered by the perforation 3^a and the purse chamber *p* of its corresponding striking pneumatic valve *t*, the path from *d* to *e*, etc., being sealed as stated above. The tube *g* is normally blocked by the membrane *h*¹. The ability of the perforation 3^a to strike a note is therefore removed.

It will be seen however that the pulse sent by the perforation 3^a along the corresponding tube *m*¹ can still pass into and through the appropriate tube *n*, and as all the tubes *n* work the selecting valves *s* of the notes next on the right or treble side, the selecting valve controlling the striking wind of the note-hole *b* uncovered by the perforation 2^a will be operated, and the note corresponding to this perforation will be accented that is to say played by wind of the other tension.

In the case of the striking of the notes corresponding to the perforations 1, there is no operation of their own selecting valves, as the perforations 3^a are absent. The fact that they themselves operate the selecting valves of the notes next on the right to them besides operating their own notes is of no concern inasmuch as the notes next on the right are not in action.

The fact that they also cancel the playing ability of the holes next on the left is immaterial for the same reason.

It will be seen in the particular example above described that the holes in the tracker bar are

capable of three functions viz., (1) they play their own notes if permitted i. e., by operating the striking pneumatic valve, (2) they cancel the playing ability of holes on the immediate left, and (3) they change the degree of exhaust of notes on their immediate right, by moving the selector valves of such notes.

Further with this particular example, the one on the left (3 or 3^a) automatically becomes an executive perforation, not being able to play itself, but serving to control the playing power of the right hand perforation (2 or 2^a) by means of the selecting valve of that note.

But when desired the perforation 3 or 3^a may play a note as well as serving as an executive perforation. Now referring to Fig. 1 it will be seen that the chamber *j* is similar for practical purposes to the chamber *i*, but that the chambers *j* are all connected by a common groove *y*. The chamber *d*¹ is similar to the chamber *d*, so that it may be said that the lower half is a duplicate of the upper half of the device.

It is obvious that if the membrane *h*¹ was drawn out, or open, it would not matter whether the membrane *h* was open or closed.

All the membranes *h*¹ are controlled collectively and normally they are closed, the chambers *j* being filled with air through the groove *y*, the groove being controlled by a valve of the usual kind operated from a special hole in the tracker bar.

When it is desired that a perforation (3 or 3^a) shall play a note in addition to serving as an executive perforation, the membrane *h*¹ will be opened by subjecting the chamber *j* to exhaust, so that the pulse through *m*¹, *d* and *d*¹ from the uncovering by a perforation (3 or 3^a) of the note-hole *b* in the tracker bar, will also pass into the chamber *e* and tube *o* by way of the tube *g*, although the tube *f* in the chamber *d* has been sealed by the pulse passing down the tube *m*² co-operating with the note-hole uncovered by the perforation (2 or 2^a) into the chamber *i* controlling the opening and closing of the membrane *h*.

Now referring to Figs. 3 and 4 it will be observed that the low degree of exhaust (soft wind) is admitted through a fly-valve 58 from a wind-way 59, and the high degree of exhaust (heavy wind) from the wind-way 57. 53^a indicate channel-ways leading to the isolated chambers 53^b of the striking pneumatic valves.

The passage-way 60 is connected to the tube *n* (Fig. 1).

When the selector device according to Fig. 3 is used the effect of a perforation 3 or 3^a will be to render a note 2 or 2^a unaccented, as the selector valve *s* will be moved to raise the valve *s* and shut off the heavy wind and the fly-valve is automatically opened so that the soft wind is effective. The selector device according to Fig. 4 will function in the reverse manner, as the selector valve *s* will be raised to open up the heavy wind and shut off the soft wind. It will be understood therefore that the function of the tubes *n* is to move the selector valves so as to accent a note, or to cause a note which in the ordinary way would be accented to be played as a non-accented or accompanying note.

It will be clear that in the exemplary forms illustrated more particularly by Figs. 1 and 5 that if the perforations 3 or 3^a are to serve to accent the note, the selector valves will be in accordance with that shown by Fig. 4. But I

wish it understood that I in no way confine myself to the selector valves shown by these views, as any other suitable form may be used. As an example of another form of selector valve reference is directed to Fig. 8.

In this view striking pneumatic valve *t*, has an isolated chamber *53^b*, a duct *70* connecting this chamber to the chamber *71* of the feeding or selector valve *s*. *p* is the striking pneumatic valve *purse chamber* and *q* the selector valve *purse chamber*. *57* and *59* are common ducts for the two kinds of exhaust. *72* is a duct connecting the striking pneumatic valve to the pneumatic *73*. It may here be stated that the striking pneumatic valves *t* shown in Fig. 7 have similar or other suitable connections to the pneumatic.

74 (Fig. 8) indicate seatings for the selecting valve, and 75 (Figs. 7 and 8) seatings for the striking pneumatic valve. 76 indicate bleed holes. 78 is a small membrane which counteracts the exhaust pull on the upper surface of the selector valve.

In Fig. 8 the perforations 3 or 3^a serve to change over from light wind to heavy wind, it being assumed that the higher exhaust is in 57.

Figs. 5 and 6, show an arrangement in which the branch tubes *m¹* and *m²* (Fig. 1) are dispensed with. In this construction the tube *m* leads into the chamber *d*. A series of diagonally arranged channels or passages 100 are provided in the upper part of the action beam which channels take the place of the branch tubes *m²* and each channel forms a communication between the chamber *e* of one note hole *b* and the chamber *i* of another note hole. The channels are sealed, together with the chamber *e*, by any suitable means.

In the construction illustrated by Fig. 1 the control apparatus is so arranged that a note hole when exposed by a perforation in the music roll operates the striking pneumatic valve of its own note, if permitted, cancels the playing power of another note hole, and operates the purse of a selector valve to change over the degree of exhaust which may be applied to a note of a further note hole, whereas in the construction illustrated by Fig. 5 the parts are so arranged that a note hole when exposed can only cancel the playing power of another note hole when it is permitted to operate the striking pneumatic valve purse of its own note. Thus in the exemplary form shown by Fig. 5, the cancellation of the playing powers of one note hole of a pair carries with it, the cancellation of the note cancelling powers of the same note hole, the playing power of which has been cancelled.

Now referring to Fig. 7 the purse chambers *p* of the striking pneumatic valves *t* are of the usual round form, the holes 50 that are drilled to supply them are preferably bored so as to enter them at the side. By such a designing allowance is made for independent holes 51 being drilled through the purse rail 52 between each purse chamber.

65 The isolated chamber *53^b* of each striking pneumatic valve, which chamber is situated above the purse chamber *p* is enlarged so as to include the holes 51.

The independent holes 51 form the ducts through which the isolated chambers are supplied with exhaust tension.

Immediately below the holes 51 are other purse chambers *q* in a lower purse rail 55.

The purses 56 covering the purse chambers *q* are fitted with pallet valves *s* which close the

independent holes 51 when the purses are inflated.

The space or channel between the lower purse rail 55 and the rail 52 forms a common wind-way 57.

The ordinary striking pneumatic valve isolated chambers are normally supplied with high tension exhaust from the common wind-way through the independent hole drilled to each chamber.

15 The isolated chambers *53^b* of the striking pneumatic valve are separated from the common wind-way 57 when the pallet valves *s* (selector valves) mounted on the purses 56 are raised to close the independent holes 51.

20 In the particular construction described with reference to Fig. 7 of the accompanying drawings there is only need as hereinafter explained for one common wind-way in each tier of the chest, as is the case with the ordinary piano-player. But it is to be understood that the chambers *53^b* may be in communication under valve control with two wind-ways as illustrated by Figs. 3 and 4.

25 It will have been noted that the control perforation of a pair of perforations, closes the independent hole or supply duct 51 supplying the striking pneumatic valve of the other or note perforation, by means of the corresponding purse and pallet valve (selector valve) in the lower rail.

30 The method of controlling the playing force of notes according to this variant, is to place the control perforation slightly backwards in relation to the note perforation, so that it will arrive at the tracker-bar slightly later than the note perforation.

35 Assuming that the normal playing is loud the later the control perforation arrives, so the note perforation will play loud until a point is reached when the control perforation is so far back that the note perforation is given full time to act completely before any action of the control perforation, and consequent shutting off of *53^b* from 57 can take place. When the point above mentioned is reached, it is not of course necessary to have a control perforation at all.

40 If the arrangement is such that the effect of a control perforation is to open a supply duct instead of closing one as above, the converse of the expression control explained above will apply; hence note perforations having no control perforation will play at their softest while the later a control perforation arrives at the tracker-bar in relation to a note perforation, so the note will play softer; the maximum loudness being obtained when both note perforation and control perforation are in dead alignment.

45 In certain cases when for reasons of space, the chest must be made in a very compact form, it may be found that notes will tend to fail when they are arranged to play very softly.

50 This is due to the fact that with a very soft note, the striking pneumatic valve, is designated to function at the same time as the selector valve *s* is actuated.

55 If as was stated above, the construction is rather compact, there may not be sufficient volume in the isolated chamber of the striking-pneumatic valve for the exhaust within it to remain sufficiently high, when it has to absorb the outer air charged volume of the valve chamber and the pneumatic.

60 This defect may be cured by various means. One way is to provide a small hole 300 drilled

80

85

150

through the upper purse rail into each isolated chamber (one only is shown in Fig. 7) so that each chamber is in communication with the common wind-way, to a slight extent, even when the supply ducts 51 are closed. Alternatively a small hole 301 may be drilled through the selecting valve itself as shown in Fig. 13 so long as the purse is not interfered with.

It is to be noted that a tracker bar of normal kind is used.

In the specification of my prior Patent No. 1,878,706 of 1932 there is described a fluid actuated expanding valve ("chimney valve") employed to actuate the striking pneumatics of a piano player to strike notes with different force by subjecting the pneumatics to different degrees of exhaust.

The present invention will now be described with respect to such a fluid actuated expanding valve which obviates the use of selector valves such as s , by functioning as a change over valve.

One way consists in leading the tube n to a change over mechanism consisting of a membrane valve, shown in Fig. 9, with which each note is supplied. Each tube n is led not to the membrane valve of its corresponding note-hole, but to the membrane valve of the note-hole it is intended to control.

Each tube o is led to a joint branching into two tubes 200 and 201, one tube 200 is led through the membrane valve 202 of its own particular note and thence by the tube 204 to the lower purse chamber of the expanding valve shown in Fig. 1 of the drawings accompanying the specification of my prior application. The other tube 201 is led direct into the upper purse chamber of said expanding valve.

Now considering a pair of perforations in the music roll, the note playing properties of the perforation 3^a will be cancelled as previously stated by the perforation 2^a. The perforation 3^a will through n move the membrane 203 of the valve 202 belonging to the note-hole of the perforation 2^a, so as to block the tube 204, with the result that the air passing down the tube o by the uncovering of the note-hole by the perforation 2^a will be prevented from entering 204, but will pass along 201 to the upper purse of the expanding valve. Assuming that the upper common wind-way of the expanding valve is charged with soft wind the note played will not be accented.

Now assuming a perforation 2^a alone. The air in the tube o will pass through both tubes 200 and 201 to the lower and upper purse chambers of the expanding valve, the diaphragm 203 being open by reason of the exhaust in the chamber 205 of the membrane valve. Both purses of the expanding valve will be actuated. But the effect of the upper purse (soft wind) will be overcome by the effect of the lower purse (heavy wind) and the note will play as an accented note.

A more elaborate form of control may be provided which allows for either soft or loud notes to be caused by an adjacent perforation in the music roll, as desired. With this arrangement an additional valve shown by Fig. 10 is inserted in the tube 201.

This additional valve has a purse 206, the purse chamber of which is also connected to the tube n . It is to be noted that the valve 207 is closed when the purse chamber is under suction. The chamber 208 is in communication with the tube 201. The outlet 209 from the valve leads to the upper purse of the expanding valve.

With such an arrangement the tube o resolves not into either 201 only, or 201 and 200 as in Fig. 9, but into either 200 or 201, because when 203 is closed by pressure 207 is opened and vice versa. As a result of this it is only one of the two purses of each expanding valve that moves, hence there is no question of one purse having to overcome the effect of the other.

With such a construction either the top or bottom common wind-way of the expanding valve may be used for the heavy wind, so that the additional perforation (3 or 3^a) in the music roll may cause a note to be either accented or unaccented.

The heavy wind may be admitted in pulse form or continuously.

It is not essential that matters be so ordered that controlled note perforations should have their controlling perforations immediately next to them.

An arrangement in which the control perforation is situated at a predetermined distance away from the note perforation is equally possible. A hole in the tracker bar for example, may cancel the playing properties of a hole, not immediately next to it, but a given number of holes removed from it.

The same hole would control the playing power of a hole the same distance away from it on its other side.

It is to be noted that there is no change in the construction of the apparatus, the diagonal grooves or branch tubes and the tubes to the selecting valves merely being suitably arranged.

It is to be understood that the invention covers the use of other suitable types of valves both as striking pneumatic valves and selector valves.

Furthermore although for the sake of convenience I have spoken of a piano player, it is clear that this present invention is applicable to players of the organ type employing the double touch system and I will have it understood that when I speak of piano players I intend to include also such players of the organ type.

Electro-pneumatic means or direct acting electrical means may be used. For example electrical means for controlling the valves. Two ways of doing this are now described.

Each hole in the tracker bar is connected by means of a tube in the usual manner to its corresponding purse in a purse rail.

Over the purses in the purse rail is situated a common wind chamber charged with exhaust tension, so that the purses will be inflated when their corresponding holes in the tracker bar are exposed.

Within the common wind chamber, and over the purses, are placed electric contacts, a set of three contacts being allotted to each purse.

It is the function of a purse when inflated to actuate its set of contacts so that two of them are made and the remaining one broken.

It is to be understood that the contacts of a set work simultaneously when the corresponding purse is inflated.

The contacts may be of any approved form, well known to the organ builder, and the telephone engineer.

In Fig. 11 the contacts of each set are designated A, B, and C, respectively.

The notes of the piano starting from the bass upwards may be considered as numbered 1, 2, 3, etc.

The selecting valves which open to admit exhaust tension to the striking pneumatic valves

B2 which is changed over, to the loud wind magnet Sb of chimney valve of note 3.

Hence hole 3 plays its note loudly as a result of the additional exposure of hole 2. We have now to see how hole 2 is itself prevented from playing a note.

It will be easily seen that this is insured by the fact that the current from A2 cannot get past C3 which is now broken.

10 When an executive perforation is absent, it will be noted that a note is played softly. Assuming that the note hole 2 is uncovered, the circuit will be from A2, C3, B1 to Sa.

15 Although in the constructions illustrated and described the cancellation of the note playing properties, etc., of a left-hand note have been referred to, it is obvious that a reversal can be made, that is to say a note-hole may cancel the note playing properties of a note-hole on the 20 right hand, and this latter note will modify the playing powers of the first note-hole. Or the perforations 3, 3a may be located on the right hand side of the holes 2, 2a.

25 With apparatus according to the present invention the advantage of being able to play existing rolls on the instrument so equipped is not lost.

30 Any known forms of expression boxes and melody valves may be incorporated, although in the simple forms of the invention the degree of exhaust is conveyed straight from the bellows to the chest.

What I claim is:—

35 1. In an automatic musical instrument of the kind referred to, the combination with each note hole of a tracker bar of control means comprising a chamber with a valved communication leading to a purse chamber of a striking pneumatic valve of a note played by the co-operating tracker bar note hole, a second chamber leading to a selecting valve governing a striking pneumatic valve of another note, a valved communication between the second chamber and the first striking pneumatic valve, said chambers being common to the co-operating tracker bar note hole, and means for opening and closing said communicating valves, whereby a note hole when exposed by a perforation in a music roll is capable of playing its own note, cancelling the playing power of another note hole, and changing over or altering the exhaust tension which may be applied to the pneumatic of a note of a further note hole.

40 2. In an automatic musical instrument of the kind referred to, the combination with each note hole of a tracker bar, of control means comprising a main chamber with a valved communication leading both to a purse chamber of a striking pneumatic valve of a note played by the co-operating tracker bar note hole and a communicating valve chamber of another note hole, a second main chamber leading to a selecting valve governing a striking pneumatic valve of a further note, a valved communication between the second main chamber and the first striking pneumatic valve, said main chambers being common to the co-operating tracker bar note hole, and means for opening and closing said second communicating valve, whereby a note hole when exposed by a perforation in a music roll is capable of playing its own note, cancelling the playing power of another note hole, and changing over or altering the exhaust tension which may be applied to the pneumatic of a note of a further note hole.

3. An automatic musical instrument of the kind referred to, comprising in combination a tracker bar, control means for each note hole in said bar, so that a note hole when exposed by a perforation in a music roll is capable of playing its own note, cancelling the playing power of another note hole, and altering the exhaust tension which may be applied to a pneumatic of a note of a further note hole, a striking pneumatic valve for each note, isolated chambers in which said valves are placed, a common wind-way with which said isolated chambers communicate, and selection valves for opening up or shutting off communication with said common wind-way.

4. In an automatic musical instrument of the kind referred to, the combination with each note hole of a tracker bar, of control means comprising a chamber with a valved communication leading to a purse chamber of a striking pneumatic valve of a note played by the co-operating tracker bar note hole, and a communication leading from said chamber to a selecting valve governing a striking pneumatic valve of another note, and means for opening and closing said communicating valve, whereby a note hole when exposed by a perforation in a music roll is capable of playing its own note, and changing over or altering the exhaust tension which may be applied to the pneumatic of a note of a further note hole.

5. An automatic musical instrument according to claim 4 in which the notes controlled are next to one another.

6. An automatic musical instrument according to claim 3, having means for maintaining a vacuum in the isolated chamber of the striking pneumatic valve.

7. In an automatic musical instrument of the kind referred to, the combination with each note hole of a tracker bar, of means which, on the uncovering of a tracker bar note hole, is adapted to actuate a striking pneumatic valve of a note allotted to said tracker bar note hole and further is adapted to actuate means to change over or alter the exhaust tension applied to the striking pneumatic of another tracker bar note hole, and also cancel the playing power of still another tracker bar note hole.

8. In an automatic musical instrument of the kind referred to, the combination with each note hole of a tracker bar, of electro-pneumatic means which, on the uncovering of a tracker bar note hole, is adapted to actuate a striking pneumatic valve of a note allotted to said tracker bar note hole and further is adapted to actuate means to change over or alter the exhaust tension applied to the striking pneumatic of another tracker bar note hole, and also cancel the playing power of still another tracker bar note hole.

9. In an automatic musical instrument of the kind referred to, the combination with each note hole of a tracker bar of a set of electrical contacts, means for actuating said set on the uncovering of the tracker bar note hole allotted thereto, each set of contacts being adapted to control a striking pneumatic valve of a note allotted to said tracker bar note hole; change over or alter the exhaust tension applied to the striking pneumatic of another tracker bar note hole, and also cancel the playing power of still another tracker bar note hole.

10. In an automatic musical instrument of the kind referred to, the combination with each note hole of a tracker bar of a set of electrical contacts including a two-way change over contact, means for actuating said set on the uncovering

of the tracker bar note hole, each set of contacts being adapted to control a change-over valve applied to the striking pneumatic of another tracker bar note hole and also cancel the playing power of another tracker bar note hole.

11. In an automatic musical instrument of the kind referred to, the combination with each note

hole of a tracker bar, of change-over mechanism effective on the uncovering of a tracker bar note hole to actuate a fluid actuated expanding valve so that the striking pneumatics are subjected to different degrees of vacuum.

CERTIFICATE OF CORRECTION.

Patent No. 1,966,798.

July 17, 1934.

GORDON BUTLER ILES.

It is hereby certified that error appears in the printed specification of the above numbered patent requiring correction as follows: In the heading to the printed specification, line 5, for the foreign filing date "December 16, 1932" read December 16, 1931; and that the said Letters Patent should be read with this correction therein that the same may conform to the record of the case in the Patent Office.

Signed and sealed this 11th day of September, A. D. 1934.

Leslie Frazer
